UNITED STATES PATENT OFFICE.

CHARLES J. BACKHAUS, OF LA PORTE, INDIANA.

DESIGN FOR A CABINET.

SPECIFICATION forming part of Design No. 24,104, dated March 12, 1895.

Application filed February 14, 1895. Serial No. 538,440. Term of patent 3½ years.

To all whom it may concern:

Be it known that I, CHARLES J. BACKHAUS, a citizen of the United States of America, residing at La Porte, in the county of La Porte 5 and State of Indiana, have invented and produced a new and original Design for Cabinets, of which the following is a specification, reference being had to the accompanying drawings, and to letters of reference marked thereon, which form a part thereof.

This design relates to cabinets for grocers' use, in which the length is greater than the width, the front of the cabinet being provided with a series of intersecting chamfered strips 15 forming spaces between them for panels, the rear of the cabinet having doors and the top being provided on its front and side edges with ornamental moldings.

In the drawings Figures 1 and 2 are perspective views of the cabinet as seen from the front and rear respectively.

The front of the cabinet is divided by intersecting chamfered strips *a* and *a'* forming

panels, the corner posts *b* forming the sides of the end panels. Above the upper strip *a* 25 there is a suitable beading *c* which extends across the front and sides of the cabinet, and upon the cabinet are corner posts between which are ornamental strips as shown.

The rear end of the cabinet is provided 30 with two frames containing glass panels and separated from each other by a strip. Above the rear edges of the shelves of the cabinet are strips forming spaces in which are glass panels. The cabinet is supported by ornamental strips *d*.

I claim—

The design for a cabinet as herein shown and described.

In testimony whereof I affix my signature 40 in presence of two witnesses.

CHARLES J. BACKHAUS.
